UNITED STATES PATENT OFFICE.

PROSPER L'ORANGE, OF KÖNIGSBERG, GERMANY.

VALVE-MOTION.

SPECIFICATION forming part of Letters Patent No. 731,699, dated June 23, 1903.

Application filed September 25, 1902. Serial No. 124,765. (No model.)

To all whom it may concern:

Be it known that I, PROSPER L'ORANGE, a subject of the German Emperor, and a resident of Königsberg, Germany, have invented a certain new and useful Valve-Motion, of which the following is a specification.

The valve-motion which forms the object of this application is intended to insure the regular closing of the valve and the simplest form of valve construction.

In the drawings, Figure 1 is a sectional view of a valve apparatus embodying this invention. Fig. 2 shows a sectional view of a modified form of valve.

Fig. 1 shows the arrangement in connection with the pressure-valve of a compressor. The valve A is an ordinary spindle-valve, the guide-casing a of which is closed at the upper end by the head g and made tight against the guide-support b by grinding. The latter is connected with the valve-seat B by means of ribs, is extended below the seat, and tightly seated below in the side of the cylinder. A boring c connects the upper end surface of the support b with the hole d in the inner wall of the cylinder. The diameter of this hole can be altered at will by means of the screw e. The distance of the hole d from the middle of the cylinder is so calculated that toward the end of the stroke the hindmost piston-ring f slides just slightly beyond the hole d and opens it, whereby the hole, and therewith the space below the head g of the guide-casing, is put in communication with the back end of the piston—that is to say, with the suction-chamber.

The operation of the valve-motion is as follows: As soon as the pressure in the working cylinder is equal to the pressure above the valve the valve begins to open automatically and after completing its stroke lies against a stop. The space formed between the head g

and the upper end surface of the guide-support b is first placed in communication with the compression end of the working piston. 45 Shortly before the end of the stroke, however, the working piston slides beyond the hole d and the back of the piston-ring directs the flow of air which is below the head g into the suction end of the working cylinder. The 50 pressure below the head g disappears and the pressure bearing upon it in the pressure-chamber presses the valve onto its seat again with a force equal to this pressure multiplied by the diameter of the guide-support. The 55 rapidity with which this is effected can be regulated by adjustment of the screw e. The pair of cylinders which produce the valve-motion and in the present example take the form of a guide can also be made as an independent organ and connected with the otherwise-guided valve. The valve-guiding contrivance used for the actuating can equally well be placed below as above the level of the valve-seat, Fig. 2. 65

Having now fully described my invention, what I claim, and desire to secure by Letters Patent, is—

The combination of the valve A, the guide-casing a closed at its upper end, the working cylinder and piston, the guide-support extending beneath the valve-seat, the passage c, d, connecting the upper end of the guide-support with the working cylinder and opening at a point where the piston will slightly pass it in the compressing stroke, and the adjusting-screw e for regulating the effective diameter of the passage. 7c 75

In testimony whereof I have hereunto set my hand in presence of two witnesses.

PROSPER L'ORANGE.
